UNITED STATES PATENT OFFICE

2,366,708

RECORDING APPARATUS

John T. Davidson and Bruce T. Bickel, Dayton, Ohio, assignors to The Standard Register Company, Dayton, Ohio, a corporation of Ohio

Application May 18, 1942, Serial No. 443,382

11 Claims. (Cl. 164—112)

This invention pertains to manifolding apparatus and recording machines, and more particularly to a punch recorder wherein business transactions, monetary values, or other data are indelibly recorded by punch marks in appropriate spaces of a printed record form.

In the present embodiment of the invention, a unitary punching mechanism is applied to a typical form of autographic register, wherein continuous superposed strips of series connected detachable printed forms are progressively advanced past a recording position at which they receive hand written inscriptions and are punch marked in areas bearing a definite relationship to the printed record form.

The punching mechanism herein disclosed is initially set by manual manipulation of selective depressible keys corresponding to the different indicia to be recorded by punch holes in the record form and thereafter the several preset punches are simultaneously actuated to perforate the previously adjusted set of superposed record forms in corresponding appropriately designated areas.

For illustrative purpose, but with no intent to unduly limit the form and arrangement or application of the mechanism comprising the invention, the apparatus forming the subject matter hereof is arranged to produce the record forms shown and described in companion application Serial No. 397,693, now matured into Letters Patent No. 2,307,036, issued January 5, 1943.

The object of the invention is to improve the construction as well as the means and mode of operation of punch type transaction registers, whereby they may not only be economically manufactured, but will be more efficient in use, automatic in operation, uniform in action, having minimum operating parts, and be unlikely to get out of repair.

A further object of the invention is to provide a punching unit of compact form which is applicable to a wide range of different types of strip feeding and registering mechanisms.

A further object of the invention is to provide an improved form of punch selecting and setting mechanism.

A further object of the invention is to provide an improved form of punch operating means.

A further object of the invention is to improve the method of production of punch identified records.

A further object is to combine and synchronize a form punching mechanism with an autographic register mechanism by which a succession of rec-

ord forms may be presented in registry and aligned relation in punch receiving position.

A further object of the invention is to provide a punch register having the advantageous structural features and inherent meritorious characteristics and mode of operation herein described.

With the above primary and other incidental objects in view as will more fully appear in the specification, the invention intended to be protected by Letters Patent consists of the features of construction, the parts and combinations thereof, and the mode of operation, or their equivalents, as hereinafter described or illustrated in the accompanying drawings.

In the drawings, wherein is illustrated the preferred but obviously not necessarily the only form of embodiment of the invention.

Fig. 1 is a perspective view of an assembled autographic register equipped with a punch recording apparatus embodying the present invention.

Fig. 1a is a detail plan view of the key board on larger scale.

Fig. 2 is a top plan view, partly broken away, of the punch unit and adjacent parts of the register mechanism.

Fig. 3 is a vertical sectional view on line 3—3 of Fig. 2.

Fig. 4 is a vertical sectional view on line 4—4 of Fig. 2.

Fig. 5 is a transverse sectional view through the punch setting mechanism on line 5—5 of Figs. 2 and 3.

Fig. 6 is a transverse sectional view through the punch mounting and operating mechanism on line 6—6 of Fig. 2.

Fig. 7 is a detail sectional view on line 7 of Figs. 2 and 3.

Fig. 8 is a detail view of a portion of the key mechanism for setting the punches.

Figs. 9 and 10 illustrate the transfer material feeding devices.

Fig. 11 is a detail plan view of a portion of the register mechanism showing the die and stripper device.

Fig. 12 is a detail view of the operating lever mounting.

Figs. 13 and 14 illustrate typical record material for use in the present apparatus and the type of record produced therein.

Like parts are indicated by similar characters of reference throughout the several views.

The illustrated embodiment of the invention is enclosed in a cabinet or housing 1, shown in Fig. 1, the left portion 2 of which houses an autographic

register apparatus, while the punch setting and operating mechanism is contained in an elevated superstructure 3, a portion of which overlies a part of the autographic register. Within the autographic register section 2 are mounted revoluble pin wheels 4 having progressive engagement in marginally punched holes 5 of superposed record strips 6 to advance such strips in unison from a source of supply through the compartment 7 of the cabinet and over a writing tablet 8.

Record material

The record strips comprise continuous series connected successions of detachable printed forms divisible upon longitudinally spaced transverse weakened lines 9 into separate record forms or sheets 10. The record forms 10 may be of any size and design, having appropriate spaces for entry of inscribed records and to receive punch marks disposed in arrangement best adapted for the particular purpose and condition of use or character of transactions to be recorded. Merely as illustrative, but with no intent to unduly limit the type of arrangement of the record forms, there are here shown record forms adapted for the returned goods and refund department of a merchandise establishment. The forms illustrated includes several spaces *a*—*a* to receive written description of the merchandise returned and the reasons therefor, the name and address of the customer to whom refund is made and by whom returned, the monetary value of the goods, and other identifying entries. Additional thereto there are provided across the top of the form a series of appropriately designated spaces *b*—*b* to receive therein punch marks indicative of the character of the transactions, such as charge, C. O. D., cash, etc., and below such series of spaces are two transverse rows of spaces *c*—*c* indicative of money values.

The imprinted forms upon each of the superposed strips 6 are identical and succeeding sets thereof are presented in registering and aligned relation on the writing tablet by operation of the pin wheels 4.

Strip feeding and autographic feature

The pin wheels are intermittently actuated through sufficient range to advance the record strips one form length at each operation by an electric motor 11 with which they are connected by a speed reduction gear train. The motor operation is initiated by a solenoid 12 upon manual depression of a starting button 13 and is operative through a predetermined cycle at the end of which it is automatically arrested. Such one cycle motor operation is quite well-known in the power operated autographic register art. Obviously, the apparatus may be manually actuated by a crank handle, or by a treadle or other device, and frictional or other strip feeding means may be substituted for the pin wheels 4. Some type of traveling pin feed device is desirable, although not essential, in order that the corresponding forms on superposed strips may be accurately registered and aligned in the recording position.

The writing tablet 8 is overlaid by a cabinet lid or cover, having therein an access opening 13', through which the positioned portions of the record strips are accessible to receive record inscriptions. The record strips are transversely interleaved in recording position with strips of transfer material. The transfer strips are auto-

matically advanced from a supply roll 14 at one side of the writing tablet 8 by intermeshing knurled rollers 15 at the opposite side thereof, between which the ends of the transfer strips are gripped and which are progressively advanced through succeeding partial rotations by the feeding operation of the record strips.

The transfer material advancing devices are best shown in Figs. 9 and 10. On the end of the shaft of one of the rollers 15 is a ratchet wheel 16 engaged by a pawl 17 carried by a vertically moving slide 18. The slide is intermittently operated in timed relation with the record strip advancement by an oscillatory lever 19, which is periodically depressed against the yielding resistance of a retracting spring 20 by a cam 21 concentric with one of the transmission gears of the pin wheel driving gear train and rotating in unison therewith. A detent pawl 22 holds the ratchet wheel and transfer material feed rollers 15 in their advanced positions.

While a set of the superposed record forms 10 are in inscription receiving position over the writing tablet 8 and beneath the opening 13' in the cabinet lid, the forward ends of the positioned forms are immediately beneath a group of depressible punch elements 23, of which there is one in registry with each transaction recording space *b* of the forms, and also one in registry with each of the value spaces *c* thereof. Thus, the punches are arranged in three banks comprising one transaction punch bank and two banks of value punches.

After receiving inscribed record matter in the spaces *a*—*a* and the appropriate spaces *b* and *c* having been punched, upon further advancement of the record strips to present the succeeding set of forms in recording position, one or more of the previously inscribed and punched forms are ejected from the apparatus through an exit opening 24, while the remainder thereof, which are separated from the overlying forms by an interposed pivoted "flutter plate" 25, are directed into the cabinet storage compartment 26.

Punch mechanism

The group of punches 23 are supported for vertical reciprocating movement in a mounting bar 27 which bridges the forward portion of the recording position in elevated spaced relation above the level of the writing tablet and the path of travel of the record strips. The punches are provided with enlarged heads at their tops and reduced perforating or cutting extremities at their lower ends. The several punches are provided with individual helical retracting springs 28. Beneath the group of punches and flush with the writing tablet 8 is a die plate 29 having therein a plurality of die openings 30 with each of which one of the punches 23 is aligned. The die plate is positioned substantially coincident with the pin wheels 4 which project above the level thereof into engagement with the record strips, while the punches 23 and die holes 30 in the plate are positioned somewhat forwardly of the pin wheels, as shown in Fig. 4.

Overlying the record strips above the die plate 29 is a stripper plate 31, which is carried by a pair of swinging arms 32 and is yieldingly held in depressed position by helical springs 33 coincident with the pivotal connections of the stripper plate arms 32. The stripper plate 31 has therein holes 34 concentric with the die openings 30, but of slightly larger size. The stripper plate holds the record strips down and pre-

vents them rising with the punches when the latter are withdrawn after each operation.

Overlying the group of depressible punches 23 is a swinging actuator plate 35 pivoted at 36 and operable against the yielding resistance of a retractile spring 37, to collectively depress selected punches 23 of the group.

Punch selecting devices

Mounted in the superstructure 3 of the cabinet and intermediate the heads of the plungers 23 and the depressible actuator plate 35 is a plurality of reciprocatory selector bars 38. Each of the bars carries a coupler plunger 39 sliding through a vertical eye or guide opening in the reciprocatory selector bar. By movement of the selector bars, the coupler plungers 39 carried thereby are shifted out of their normal positions wherein they register with the openings 40 in the depressible actuator plate into registry with one or another of the reciprocatory punch members 23 of the corresponding bank. The degree of movement of the selector bars and the particular punch plungers into aligned relation with which the coupling plungers 39 are moved is determined by depression of corresponding keys 41 of the selector key board at the right of the cabinet superstructure 3. So long as the selector bars 38 and their plungers 39 are in normal or home positions, the plungers 39 being in registry with the holes 40 in the actuator plate, the depression of the latter is idle. The upper ends of the plungers 39 under such condition enter the holes 40 as the actuator plate is depressed and perform no function. However, upon movement of a selector bar 38, the coupler plunger 39 carried thereby is moved out of registry with the corresponding hole 40 in the actuator plate into a position immediately over a selected punch member 23 and beneath an imperforate area of the actuator plate. Upon subsequent depression of the actuator plate by swinging movement of an operator lever 42, all of the selectively positioned coupler plungers are simultaneously depressed to simultaneously depress the corresponding punches into perforating engagement with the portions of the strips then in recording position. The operator lever 42 is pivoted for swinging motion and is formed with a projecting foot 43, which by such swinging motion is thrust through an opening 44 in the top of the register cabinet into engagement with the depressible actuator plate 35 to effect operative depression of the plungers.

The selector bars 38 extend toward the right (Figs. 1, 2 and 3) beneath the keyboard. There are two banks of ten value punches each and four banks of five value keys each, and also one bank of five transaction punches and one bank of five transaction keys. The selector bars are arranged in pairs. Each pair of selector bars is common to one bank of value punch members 23. Each selector bar of a given pair is common to half the number of punch members comprising the corresponding bank thereof. There are ten punch members shown in each of the first two banks, which in the illustrated record system pertain to monetary values identified on the record sheet. There are only five control keys associated with each selector bar 38. There are, however, only five punch members shown in the third bank thereof, which in the instant system pertain to the different business transactions, and only one selector bar 38 is associated therewith and controlled by five

keys 41 of a single key bank. Of the pairs of selector bars pertaining to each bank of ten punch members, one such bar controls the selection of one from the group of five punches at the right and the other bar controls the selection of one from the group of five punches at the left of the related bank of punches under the selective action of one of the five keys pertaining to the particular selector bar. Each selector bar is stepped or formed with a series of offsets or stop shoulders 45, each of which is engageable with a different selector key 41 of the corresponding key bank when depressed.

Connected to each selector bar 38 is a retractile spring 46, which is tensioned by the swinging motion of the operator lever 42 to retract the bars 38 until arrested by a depressed key 41 of the corresponding bank. Each of the selector bars is normally locked against retraction by a corresponding pivoted, spring operated detent 47 which engages with a shoulder 48 of the bar 38. The selector keys 41 are mounted for vertical reciprocatory movement through the top of the housing 3 and through a horizontal wall or guide plate 49 therein. The selector keys are depressible against spring tension. Each key may be supplied with an individual retracting spring, but in the drawings an elongated helical spring cable 50 formed into a succession of bights is common to all the keys of each bank. The spring cable 50 is attached at its opposite ends to the top of the housing 3 as at 51 and extends thence alternately through slotted openings 52 in the succeeding key stems 53 and through holes in dependent brackets 54 attached to the top of the housing. The key stems 53 have divergent tongues 55 punched therefrom which afford stops engageable with the top of the housing to limit the retraction of the keys under influence of the spring cable 50. The lower ends of the key stems 53 are bifurcated at 56 to different extents and straddle the selector bars 38. So long as the keys are in their normal elevated positions, the selector bars may move freely through the terminal slots of the keys. However, upon depression the unslotted portion of the depressed key is projected into the path of one or another of the selector bar steps or shoulders 45 to arrest the retraction of the selector bar under influence of its spring 46 after a degree of sliding movement corresponding to the depressed key. To unlock the selector bar for such movement by disengagement of the locking detent 47 from the shoulder 48 of the bar, there is provided upon the top of the key guide plate 49 a reciprocatory detent or latch plate 57 having spaced holes therein through which the key stems 53 project. There is a separate detent or latch plate for each bank of keys. The latch plates 57 are spring tensioned. Each plate may be provided with an individual retracting spring, but in the present instance a helical spring cable 58 is employed, which is common to the slides of the several banks of keys. The retractile spring cable 58 is attached at its opposite ends to the housing partition or guide plates 49. Intermediate its ends it is formed into a succession of reverse bights which are alternately engaged about projections 59 upon the housing partition or guide plate 49 and about like projections 60 upon the separately movable latch plates 57. The construction is such that either of the latch plates may be moved longitudinally by the depression of any key of the corresponding bank, and upon release will be retracted by the spring 58 into

locking engagement with the depressed key. In the key stem 53 is formed a divergent cam tongue 61, which upon depression of the key stem through the corresponding hole in the latch plate 57 serves to slidily move the latch plate longitudinally against the tension of the spring 58. As the latch plate 57 is so moved, a dependent finger or flange 63 on the end of the latch plate engages with a shoulder 64 of the selector bar detent 47 to elevate the detent out of engagement with the shoulder 48 of the selector bar, as shown in Fig. 8, thereby permitting the spring 46 to retract the selector bar until arrested by engagement of the corresponding shoulder 45 with the depressed key. As the cam tongue 61 passes beyond the latch plate 57 and the spring 58 retracts the latch plate, the cam tongue 61 engages therebeneath to lock the key in its depressed position.

Connected to the rock shaft 65 of the operating lever 42 for unison oscillation are spaced rock arms 66 to which is pivoted a sliding frame comprising side members 67 interconnected by intermediate tie rods 68 and 69 provided with rollers 70 which ride to and fro in grooved tracks 71 on the inner sides of the housing wall. The selector bar retractor springs 46 are attached to the tie rod 69 of the sliding frame. As the rock arms 66 swing with the depression of the operating lever 42, the interconnected frame is slidily shifted in the tracks 71 to increase the tension on the springs 46 attached to the selector bars to insure full stroke movement of any released bars 38 until arrested by depressed keys 41. This insures proper positioning of the coupling plungers over the particular punch members to be actuated and upon further depression of the operating lever 42 against the actuator plate 35, all of the selected punches are actuated in unison. Upon return oscillation of the operating lever 42, the sliding frame 66-67 engages the ends of any operated selector bars 38 and as the tension of the springs 46 is being relaxed, pushes the operated selector bars back to normal or home position. During such return motion of the operating lever, a cam nose 71 thereon engages a stud 72 projecting from a rock arm 73 connected to a rocking bar 74 which extends across the several latch plates 57. Each of the latch plates has an upturned finger or flange 75 engaged by the rock bar upon oscillation thereof to operate the latch plates against the tension of their retracting spring 58 sufficiently to release any selector keys 41 which then may be held in depressed position by engagement of their cam tongues 61 beneath the latch plate. The operating lever is retracted by a coil spring 76 about its pivotal mounting. With restoration of the selector bars and release of the depressed keys by retraction of the latch plates incident to the retraction of the operating lever by the spring 76, the parts are returned to normal relation preparatory to the next operation.

Immediately above the cam tongues 61 upon the key stems 53 are shoulders 61' which prevent retraction of the latch plates 57 through full stroke under influence of the spring 58 and so retains engagement of the operated latch plate with the locking detent 47 to prevent its reengagement with the shoulder 48 of the selector bar until the keyboard is cleared and all keys returned to normal.

From the above description it will be apparent that there is thus provided a device of the character described possessing the particular features

of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described our invention, we claim:

1. A recording apparatus, wherein record indicia are identified by punch marks in appropriate spaces of a printed form, presented in record receiving position by strip feeding and registering devices engageable with superposed continuous record strips of series connected detachable record forms, having thereon appropriate spaces for entry of inscribed records and contiguous thereto a plurality of appropriately designated punch receiving spaces for progressively advancing the record strips through successive form length movements and arresting the successive record forms with the appropriately designated punch receiving areas of superposed forms in registry with each other and with the corresponding punches, including a plurality of independently operative punch members, one for each of the designated punch receiving spaces of the form, a common actuator therefor, punch selective mechanism including a plurality of reciprocatory selector bars, coupling devices each common to a plurality of punch members carried by the respective selector bars and movable into operative relation with a selected punch of the plurality by movement of the corresponding selector bar to enable operative movement of the punch by actuation of the common actuator, said coupling devices being movable relative to and independently of the selector bars under influence of the common actuator to operatively actuate the corresponding selected punch, a series of setting keys pertaining to each selector bar determining the degree of movement thereof necessary to present the punch coupler in operative relation with the corresponding punch, a detent device for locking each of the selector bars in retracted position against their actuating influence and disengaged by operation of any one of the setting keys pertaining to the particular bar, and an operator device for transmitting longitudinal selective movement to the selector bars until arrested by a corresponding key and upon further movement operating the common punch actuator to thrust selected punches through the record forms then in recording position.
2. A recording apparatus, wherein strip feeding and registering devices advance superposed continuous strips of series connected record forms past a recording position and arrest the strips with succeeding forms thereof with appropriately designated spaces upon the superposed strips in registry with each other and with a series of punches engageable therein, including a plurality of independently operable punch members disposed in rows in relation to the positioned form to punch mark the form in corre-

sponding spaces of the form appropriated to different record purposes, an actuator common to all the punches, punch selector mechanism including a pair of selectors for each row of punch members, a single adjustable punch coupler carried by each selector for selectively coupling any one of a plurality of punches with the common actuator for actuation thereby, a plurality of setting keys pertaining to each punch coupler for optionally associating the punch coupler with any one of the plurality of punches to which it is common, and an operator device for transmitting motion to the selected punch couplers independently of the unselected punch couplers and to the punch actuator.

3. A recording apparatus wherein a continuous strip of series connected detachable pre-printed record forms is progressively presented in a recording position to receive punch marks in spaces of succeeding forms comprising the strip appropriated to different record data, by strip feeding devices which advance the continuous strip of detachable forms through a step by step movement and arrest the succeeding forms with preprinted areas appropriated to reception of punch indicia in registry with the corresponding punches, including a plurality of independently operable punches arranged in lines with individual punches thereof in registry with corresponding record spaces of the positioned form, punch selective means for optionally selecting any one of a group of punches for operation, including a pair of selectors for each line of punches, a single punch coupler member associated with each selector, and an actuator device common to a plurality of punches for energizing the selected punches of the plurality to perforate the record form in the corresponding space thereof.

4. A recording apparatus, wherein a continuous strip of series connected detachable pre-printed record forms having thereon spaces appropriated to different record data are successively presented in a recording position to receive punch marks in selected areas thereof, and is progressively advanced through a step by step movement by strip feeding devices and arrested at the limit of each advancement with correspondingly appropriated printed spaces in registry with corresponding punches, including a plurality of independently operable punch members arranged in rows, one for each punch receiving space of the form, a plurality of setting keys, one for each punch member, a selective mechanism common to a plurality of punches for conditioning one of the plurality corresponding to a particular setting key for operation, including a pair of selectors for a single row of punches, a single punch coupler member associated with each selector, and an actuator energizing the preconditioned punches to perforate the positioned record form in the area thereof corresponding to the conditioned punch.

5. A recording apparatus, wherein a continuous strip of series connected detachable pre-printed record forms having thereon spaces appropriated to different record data are successively presented in a recording position to receive punch marks in selected areas thereof by strip feeding devices operative to advance the strip through successive step by step movements and arrest succeeding forms thereof with appropriately printed designated spaces in registry with corresponding punches, including a plurality of

independently operable punch members, one for each punch receiving space of the form arranged in rows, a plurality of setting keys for each punch member, and a pair of punch selective devices common to a single row, a single punch coupler member associated with each selective device and a plurality of keys conditioning for actuation the particular punch corresponding to an operated key, and an actuator for the conditioned punch.

10 6. In a recording apparatus, a plurality of independently recording elements, a common actuator therefor, a selector comprising a reciprocating bar, a coupler member carried thereby and movable into operative relation with any one of the recording elements by reciprocation of the bar to condition said recording member for operation by the common actuator, a locking detent for the selector bar, a plurality of keys controlling the movement of the bar to different ranges of movement according to the key operated, a movable detent member for temporarily locking an operated key in its operated position, an operative connection between the key detent and the selector bar detent by which the detent is disengaged to release the selector bar upon operation of a key, and means for temporarily preventing reengagement of the detent and selector bar so long as a key remains in its operated position.

15 7. A recording apparatus, including a plurality of independently operable recording members, a common actuator therefor, a selector mechanism comprising a reciprocating bar, a coupler carried thereby for operatively interconnecting any one of the recording members with the common actuator, a plurality of setting keys determining the range of movement of the selector bar, a detent for the selector bar, disengaged by operation of any one of the keys, a detent for an operated key of the plurality, and an operating device for the common actuator for the recording devices operative to also release the operated key.

20 8. A recording apparatus for operation upon a continuous strip of series connected detachable preprinted forms, each having an area appropriated to inscription of record data and between such area and the head of the form a series of defined punch receiving area appropriated respectively to transaction identification and to momentary values wherein the strip is progressively advanced by strip feeding devices past an inscription receiving and punch receiving position, a writing tablet, over which the strip is advanced, a group of independently operable punches one for each of the transaction identification and monetary value identification punch receiving areas positioned closely in advance of the writing tablet in the direction of advancement of the strip, and beneath which the strip is advanced, strip arresting means for accurately registering the inscription receiving area of the strip with the writing tablet and the respective transaction and monetary identifying areas in registry with the corresponding punches of said group at the limit of each strip feeding operation, a series of transaction identification keys and of monetary value keys, selective means for conditioning punches corresponding to manually operated transaction identification and monetary value identification keys for operative action independently of other punches of the group, and an actuator common to all of the preconditioned punches for operating said punches in unison to punch holes in certain predetermined transac-

tion and monetary value identification areas of the positioned, preprinted form.

9. A recording apparatus for identifying the character and the monetary values of business transactions inscribed on preprinted forms by punching holes in areas appropriated to transaction and monetary value identification, wherein a continuous strip of series connected preprinted forms are progressively advanced past a recording position, including an inscribing position and a multiple punching position arranged in aligned relation in the direction of advancement of the strip, a group of independently operable punches at the latter position, strip arresting means for accurately registering a preprinted area of the strip in inscribing position and simultaneously registering each of the areas appropriated to transaction identification, and monetary value identification with a corresponding punch, a set of manually operable keys each bearing a different transaction designation, and a set of keys each bearing a different monetary value designation, selector means for preconditioning transaction indicating punches and value indicating punches corresponding to corresponding keys upon operation of the keys, preparatory to simultaneous operation thereof by a common actuator.

10. A recording apparatus for recording upon a continuous strip of series connected detachable preprinted forms the character of a business transaction, data pertaining thereto and the monetary value involved in the transaction, wherein a record strip is progressively advanced by strip feeding devices through a step by step movement and periodically arrested in record position over which the forms are successively arrested to receive a written inscription, a group of punches disposed contiguous to the writing tablet, appropriated respectively to identification of the character of different transactions and different monetary values with which prescribed areas of the arrested form appropriated to like transaction and value indicia register when the form is in record receiving position, a group of punch selection keys, including a set of trans-

- action keys appropriated to indication of particular transactions, including "Charge," "C. O. D.," "Merchandise Credit," and "Cash," and a set of keys appropriated to different monetary values, 5 operative connection controlled by operation of said keys for preconditioning the corresponding punches for operation upon an arrested form, and actuating means for effecting operation of the conditioned punches corresponding to the 10 selected keys to engage the arrested form in the correspondingly appropriated spaces thereof.
11. A recording apparatus for recording indicia upon a continuous strip of series connected detachable preprinted forms, each having a space 15 thereon appropriated to reception of hand written data, and having at the head of such form a series of spaces appropriated to indication of particular business transactions and a further series of spaces appropriated to indication of monetary values, including a writing tablet over 20 which the strip is progressively advanced through step by step movement by strip feeding devices and arrested in record receiving position with the space appropriated to hand written data in 25 registry with the writing tablet, a group of punches in proximate offset relation with the writing tablet in the direction of advancement of the strip thereover, with which the spaces appropriated to indication of business transactions 30 and monetary values register when the form is arrested in record receiving position a group of control keys for said punches, including a set of keys designated for different business transactions and a set of keys designated for different 35 monetary values corresponding to the spaces of the form appropriated to business transaction and monetary value indicia, operative connections between the respective keys and the corresponding punches, and means for actuating the 40 selected punches to indicate in the appropriate spaces of the form the character of the transaction and the monetary value thereof.

CERTIFICATE OF CORRECTION.

Patent No. 2,366,708.

January 9, 1945.

JOHN T. DAVIDSON, ET AL.

It is hereby certified that error appears in the printed specification of the above numbered patent requiring correction as follows: Page 5, second column, line 51, claim 8, for "momentary" read --monetary--; and that the said Letters Patent should be read with this correction therein that the same may conform to the record of the case in the Patent Office.

Signed and sealed this 12th day of June, A. D. 1945.

Leslie Frazer

(Seal)

Acting Commissioner of Patents.
